GAUGING DEVICE FOR LARGE PARABOLIC ANTENNAS

Joseph F. Bell, Elmhurst, Ill., assignor to Andrew Corporation, Orland Park, Ill., a corporation of Illinois
Filed June 8, 1964, Ser. No. 373,318
4 Claims. (Cl. 33—174)

The invention relates to a gauging device for curved surfaces, and more particularly to a gauging tool or instrument for use in adjusting a curved surface contour, such as that of the parabolic "dish" of a large directional antenna.

As the electronic communications arts have pushed toward greater and greater sensitivity and directionality of antenna systems, larger and larger structures have been employed for the parabolic reflectors used for high signal gain. As is well known in the electronic (and optical) arts, the narrowness of the concentration of an electromagnetic energy beam, i.e., the directional gain, may be accomplished by increase of the aperture or parabolic arc of the reflector. Accordingly, larger and larger parabolic "dishes" have been, and are being, used.

The full benefit of increase of reflector size is obtainable only by the highest of precision in maintaining the exact desired shape of the reflector. Because the increase in aperture represents an increase in distance of the peripheral portion from the feed (which term of course includes use in reception) at the focus, extremely precise preservation of the exact desired curvature is required in this region. When a reflector is constructed of aperture dimensions comparable to the dimensions of a large building, the establishment and preservation of a surface shaping or contour which is of the required curvature in all regions becomes difficult. The reflector surface construction virtually universally employed is a "skin" of conducting mesh, supported on an appropriate backing framework. Since it is a virtual impossibility to construct the framework in such a manner that the requisite accuracy of shaping can be done by relying solely on the framework for definition of the shape, it has been found necessary to provide adjustable supports for the skin, distributed with sufficient frequency to permit the proper shaping thereof by adjustment of the spacing from the framework, thus permitting the formation of the requisite exact curvature.

The present invention lies in a tool or gauge which is suitable for use in making the adjustments just mentioned, in installing the skin upon its supporting framework to produce the exact contour desired, without introducing a vast amount of complex measuring and calculation, but without imposing prohibitive costs (or perhaps sheer impossibility) on the construction of the gauging equipment.

A more or less conventional way of inspection or measurement of a curved surface with regard to conformity to a standard is the use of a template. A block or sheet of wood or metal may be formed with an edge or surface of the desired shape and laid on the surface to be inspected or adjusted, with exactness of conformity being visually observed at each point. Such a use of a template is essentially impossible when dealing with structures such as the 60-foot-diameter reflector for use with which the embodiment of the invention later to be described is designed. It is unnecessary to point out in detail the problems of both fabrication and use of such a template, in monitoring the exact curvature of a structure of the size just mentioned.

The size of reflector here involved accordingly cannot employ the tools and methods which are conventional in measuring the surface shape in smaller structures. One possible solution to the problem, of course, is the point-

2

by-point measurement of slope with respect to reference vertical and horizontal directions, but the making of such measurements is extremely difficult, particularly where the skin is to be adjusted upon a completely erected framework, i.e., in its use orientation.

It is accordingly the object of the present invention to provide a relatively simple type of gauging device or tool which is capable of being used in a manner which is reasonably comparable with the manner in which a template block or sheet is used with smaller reflector constructions. In general, this object has been accomplished by providing a gauging device or instrument having certain features of both its construction and its manner of operation resembling that of the usual template, but with important differences which will be seen. The present invention may perhaps be best understood by considering it as a device which in essence converts a curved contour, which is in itself very difficult to inspect visually for error, to a linear or planar contour, the inspection of which for accuracy is a well-known simple routine operation in structure of large size, such as walls of buildings, etc.

This conversion is made by mounting a support member in a reference orientation extending across the region whose curvature is to be monitored, the support member bearing feelers spaced along the curved surface and urged into contact therewith, each feeler being associated with a position-indicator (its outer end in the simplest and most desirable embodiment), all the indicators being in alignment when the predetermined correct curvature exists in the surface upon which the feelers rest. With this construction, it is unnecessary to attempt to provide such a prohibitive structure as (for example) an exactly shaped prefabricated template. The alignment (or misalignment) may readily be observed with a simple optical instrument such as a transit or telescope, and, by provision of suitable calibration markings on the indicators, the degree of misalignment, and the required amount of adjustment for alignment, may readily be determined and communicated to the person making the adjustments.

The broad principle of construction just described is, in accordance with the further teachings of the invention, implemented in a relatively simple and inexpensive manner, but without loss of accuracy, in the embodiment to be described, which accordingly incorporates the further teachings of the invention which may best be understood from consideration of the various features of its construction, best described by reference to the attached drawing, in which:

FIGURE 1 is a side view in elevation showing the overall construction of a gauging tool or instrument employing both the broader and narrower aspects of the features of novelty of the invention, along with the dotted indication of a parabolic reflector construction with which it is designed to be used;

FIGURE 2 is a view in front elevation of the device of FIGURE 1;

FIGURE 3 is a fragmentary enlarged view of a portion of a mounting assembly, constituting a portion of the device, employed for rotational mounting of one part of the tool or instrument at the center of a reflector;

FIGURE 4 is a sectional view taken along the line 4—4 of FIGURE 3, in the direction indicated therein by arrows, and also showing the end of a shaft constituting a portion of the device, omitted in FIGURE 3 for clarity of illustration;

FIGURE 5 is a fragmentary sectional view illustrating the mounting of the opposite, or front, end of the central shaft of the device;

FIGURE 6 is an enlarged view of a feeler and indicator rod and its support and mounting, constituting a portion

of the device, and shown partially in elevation and partially in section; and

FIGURE 7 is a view in side elevation of the assembly of FIGURE 6.

As seen in FIGURES 1 and 2, a contour gauge made in accordance with the invention, generally indicated by the numeral 20, is shown as it is employed in the adjustment of the precise surface contour of a parabolic reflector, generally indicated by the numeral 21 and shown in highly schematic dotted form, since it constitutes no part of the present invention. The reflector 21 has a "skin" 22 (of the usual mesh or screening of the fineness appropriate for the frequency of intended operation). This conducting surface is supported on a framework, schematically illustrated at 24, by means of adjustable supports 26, distributed in suitable fashion.

The gauge 20 has a shaft 28 which is supported in a first bearing generally indicated at 30, at the center of the dish or reflector structure, and a second bearing generally indicated at 32, which is held centered on the axis by wires or similar mooring means 33 extending out to the framework.

Mounted on the shaft is a gauging assembly framework 34, which is counterbalanced by a counterweight framework 36, bearing a counterweight 38. The gauging assembly framework 34 bears gauging rod assemblies 40a, 40b, etc., which are radially spaced along the framework or arm 34, and extend in parallel fashion to contact the skin 22. The framework 34 consists in general of an outer radial portion 41, and an inner radial portion 41a, the latter being formed of slightly angularly related individual lengths to form an overall more or less curved member roughly approximating the curved shape of the reflector. This entire assembly is rigidized by cross braces 42 and diagonal braces 43 (only examples of these being illustrated), and tie-wires 44 are suitably tightened on the main framework and on transverse tie-bars 45. Further, suitable tie-wires 46 connect portions of the gauging assembly framework or arm 34 with the counterweight framework 36. (All tie-wires are omitted from FIGURE 1 for clarity.)

As will be readily understood, the bracing and rigidizing of the movable assembly is shown only suggestively in the drawing, which omits not only much of the structure employed for this purpose, but also the turnbuckles and similar adjustment means employed in the formation of the overall highly rigid, counterbalanced, and properly oriented rotatable assembly mounted on the shaft 28.

The manner of mounting the shaft 28 at the inner bearing 30 is shown in FIGURES 3 and 4. A mounting plate 48 has reinforced radial extensions 49 forming a spider adapted for rigid mounting at the center of the dish or reflector. As will readily be understood by those skilled in the art, the adjustments here involved are made prior to the installation of the feed, and the spider support of the inner portion of the present gauging device may engage the portion of the reflector framework designed for mounting of the corresponding portion of the feed assembly.

The plate 48 is centrally apertured at 50, and this aperture is surrounded by mounting blocks 52 on the back of the plate 48. The blocks 52 have radial threaded apertures 54 receiving adjusting bolts 56 which extend in through the blocks 52. The inner end of each bolt 56 is annularly grooved at 58, and is capped by a dog 60, having a well-bore 62 seating the rounded extreme end 64 of the bolt 56. The dogs 60 are secured in place by pins 66 driven through suitable apertures therein and seating in the grooves 58.

The inner surface 68 of each dog 60 is a conical segment, thus forming in essence a rearwardly facing adjustable conical seat. A mating conical surface 70 is formed on a plug 72 welded into the end of the tubular shaft 28. The outer end of this plug has mutually perpendicular transverse bores 74 and 76 permitting rotation by insertion of a suitable rod.

As seen in FIGURE 5, the front end of the tubular shaft 28 is secured to an internal plug 78 by bolts 80. The plug 78 is formed with a shoulder at 82 and the front end portion 84 extending therefrom is rotatable in a bearing sleeve 86 which extends through a boss 88 welded to a heavy plate 90. The plate 90 is suitably apertured for the securing of the supports 33 which maintain its centered relation, as previously described. A washer 92 is secured by a bolt 94 and lock-washer 96 to the outer end of the portion 84 within the bearing 86, thus completing the outer end of the rotatable assembly.

FIGURE 6 shows the construction and mounting of one of the gauging rods 40, all of which are essentially identical except for body length. The body is formed from a tubular rod 98. This is mounted in suitable apertures in an outer slide bracket 100 and an inner slide bracket 102, secured to suitable mounting plates 104 and 106, respectively, these latter being mounted on the respective outer and inner portions 41 and 41a of the framework 34. (As indicated in the drawing, the plate 106 is tilted with respect to the bracket 102, and the degree of this tilt of course varies with the radial region of the arm, as does the length of each rod.) The brackets 100 and 102 are provided with suitable bearing liners 108 and 110, such as a nylon composition, secured in place by screws 112.

Inward of the bracket 100, a washer 114, retained by a pin 116 driven through the tube, bears on one end of a coiled compression spring 118, the other end of which bears on the bracket 100. The spring 118 thus urges the rod inwardly toward contact with the curved surface under measurement. A further pin 120, near the opposite bracket 102, acts as a limit stop for this motion under the urging of the spring 118.

To the lower end of the tube 98 is welded a base 122 having an ear extension 124 apertured at 126 to receive a reduced portion 128 of a stud 130, having a head 132 serving to mount a nylon wheel 134 journalled on a suitable bearing liner 136. This assembly is held in place by a nut 138 threaded onto the end 140 of the stud 130.

The wheel 134 is formed with a relatively fine or thin edge 142, and the rotational position or orientation is maintained by a guide rod 144 which slides in a guide aperture 146 in the bracket 102 and is secured to the base 122 of the rod assembly by a pin 148.

The pin 144 maintains the rotational axis of the wheel 134 at all times radial, and the relatively fine edge or support surface of the wheel 134 assures that the longitudinal positioning of the rod under the urging of the spring 118 is determined solely by the position of the surface against which the spring urges the wheel, and is free of error produced by slope or pitch. It will be seen upon study that the use of a wide contact surface on the edge of the wheel 134 would introduce an error in the correspondence between longitudinal rod position and exact location of the point of the surface under measurement in alignment with the center of the rod. The mounting means for the wheel, previously described, aligns the contact point of the wheel with the rod, as seen in FIGURES 6 and 7, and the narrow point of contact prevents the radial pitch or slope from affecting the accuracy of the indication given by the longitudinal rod position.

In the outer end of each tubular rod 98 is a calibration plug 150, with scribed markings 152, preferably at equal fractional parts of an inch from the end 154. The end of the tubular rod 98 is slotted at 156 and a clamp 158 is used to tighten the sliding fit of the plug 150, after exact adjustment to the desired overall length.

The lengths of the rod assemblies, as grossly constructed and as finally adjusted by the positioning of the calibration plugs just described, may be set by calculation so that the successive differentials in length, as a function of radial distance from the axis, form the exact parabolic shape desired. When this is done, all of the outer ends of the calibration plugs will be in exact alignment when

the surface underlying a given angular position of the gauging tool is exactly of the shape desired. Any deviation from the desired curve appears as a deviation from straight-line orientation, and the amount of required adjustment of the region of contact of any given rod may be determined merely by observation of the number of divisions or markings by which that rod fails to be in the proper alignment. The use of a transit or similar sighting device permits ready observation and communication of the required adjustments.

It will of course be obvious that many variants of the particular construction illustrated may be employed without departure from the teachings of the invention. Furthermore, a variety of dimensions, materials, etc., may be used. The selection of materials, dimensions, etc., will of course vary greatly with both the details of construction of the gauging device and with the size and desired accuracy of the surface to be adjusted or otherwise measured or observed in this manner. The particular embodiment shown in the drawing is one which has been very successfully employed for the contouring of the reflecting surface of a parabolic reflector of 60-foot diameter. In this particular construction, the gauging arm was formed of a plurality of longitudinal sections bolted together by use of suitable flanges (not illustrated) provided for this purpose, in order to permit ready transportation and assembly and disassembly, the required 30-foot radius of the gauging arm being formed of a plurality of pieces each less than eight feet long. In this particular construction, there was employed a shaft of 8-inch diameter aluminum tubing of a length of approximately fifteen feet, and aluminum was also used in the form of angle and similar stock in the framework. The adjustability provided by the calibrating plugs permits field assembly and resetting to exact dimensioning after bolting together of the frame and rigidizing by the guys, etc.

As earlier indicated, persons skilled in the art will readily devise many forms of the invention, some of which will readily be obvious while others will become apparent only after study. Accordingly, the scope of the protection to be afforded the invention should not be limited to the particular embodiment illustrated and described, but should extend to all utilizations of the teach-

ings of the invention as defined in the appended claims, and equivalents thereof.

What is claimed is:

1. A surface contour gauge for use in shaping large parabolic antenna reflector comprising:
- (a) a rigid rotatable support,
  - (b) a first bearing at the inner end of the support adapted to be mounted at the center of the reflector and a second bearing at the outer end of the support having laterally adjustable mounting means for aligning the support for rotation about the parabolic axis,
  - (c) a radial arm on the support,
  - (d) parallel gauging rods spaced along the arm and spring-urged inwardly in the axial direction, the lengths thereof decreasing substantially parabolically with radial distance from the axis,
  - (e) and substantially identical sets of longitudinally spaced markings on the outer ends of the rods, whereby conformity of the reflector to the parabolic contour may be observed by viewing of the alignment of the outer end portions of the rods, and the amount of required adjustment of the surface at any point is indicated by the measure of misalignment provided by the markings.
2. The gauge of claim 1 having wheels on the inner ends of the rods mounted on radial axes of rotation directly aligned with the rods.
  3. The gauge of claim 2 having the markings on longitudinally adjustable end portions of the rods.
  4. The gauge of claim 3 having a counterweight opposite the arm.
